UNITED STATES PATENT OFFICE.

ARNOLD A. WEIGEL, OF CHICAGO, ILLINOIS, ASSIGNOR, BY MESNE ASSIGNMENTS, TO
SOPHIE L. WOODS, OF CHICAGO, ILLINOIS.

ANTIFRICTION-BEARING.

1,320,722.

Specification of Letters Patent.

Patented Nov. 4, 1919.

Application filed March 3, 1919. Serial No. 280,292.

To all whom it may concern:

Be it known that I, ARNOLD A. WEIGEL, a citizen of the United States, and a resident of Chicago, in the county of Cook and State of Illinois, have invented certain new and useful Improvements in Antifriction-Bearings; and I do hereby declare that the following is a full, clear, and exact description thereof, reference being had to the accompanying drawings, and to the letters of reference marked thereon, which form a part of this specification.

This invention relates to improvements in antifriction bearings and consists of the matters hereinafter described and more particularly pointed out in the appended claims.

The invention is herein illustrated as applied for use in connection with a side bearing for railway cars and more particularly to a side bearing adapted to be mounted on the truck bolster of said car. The objects of the invention, as well as the many advantages thereof, will be more apparent as I proceed with my specification.

25 In the drawings:

Figure 1 is a view representing a longitudinal section through the improved antifriction bearing, the plane of the section being indicated by the line 1—1 of Fig. 2.

30 Fig. 2 represents a top plan view of the same, with a part of the casing shown as broken away, to more clearly illustrate the interior construction.

Fig. 3 represents a transverse section 35 through the improved antifriction bearing, the plane of the section being indicated by the line 3—3 of Fig. 2.

Fig. 4 represents a view similar to that shown in Fig. 1, but with the parts arranged 40 in a different relation.

Fig. 5 represents a perspective view of a filler block embodied in my improved antifriction bearing.

Referring now in detail to that embodiment of the invention illustrated in the accompanying drawings:—10 indicates the casing, in the form of an open bottom, rectangular shell, of a length somewhat greater than its width. Said casing has upper side and end walls 11 and 12 respectively, inwardly extending side flanges 13 at its top, which define an elongated top opening or slot 14, and ears 15 at its bottom corners by means of which it is attached to a truck bolster 16 of a railway

car. In the side and end walls, near the bottom edges thereof, are provided the usual ventilating openings.

17 indicates a filler block (shown in perspective in Fig. 5), located within the casing, which rests upon the truck bolster 16. Said filler block comprises upright, spaced-apart side members 18, 18, which are connected together at their middle bottom parts by a transverse bridge 19, and at their ends 60 by brace bars 20. The top surface 21 of the bridge piece 19 is converged slightly upwardly from its transverse median line, toward its ends and preferably to said top surface is riveted a wear plate 22 which is 70 formed or bent so as to fit said converging top surface.

Normally engaged upon said wear plate and capable of an endwise rolling movement thereon is an antifriction element 23. This 75 element is in the form of a cast metal roller having a hardened steel center pin providing laterally extending trunnions 24. The roller is of a width approximating that of the slot 14 before mentioned, and is of such 80 a diameter that its top part projects through said slot into a plane above that of the top of the casing, so as to be engaged by a complementary bearing surface on the body bolster 25, while the trunnion pin is of a length 85 equaling the width of the filler block.

The inner opposed corners of the side members 18 of the filler block 17 are rounded as shown to provide bearing pockets 26 to be engaged by the trunnions 24 when the 90 roller reaches the end of its path of travel in either direction on the wear plate, said pockets being so arranged that the roller will never bear upon or engage against the end walls 14 of the casing. The bearing 95 pockets 26 include relatively short, oppositely disposed surfaces 26^a which are inclined downwardly toward the middle of said filler block, in planes indicated by the dash and dot lines, as shown in Figs. 1 and 4. 100

The wear plate 22 terminates at each end short of the end of the path of travel of the roller, so that the roller is released from contact with the wear plate just shortly prior to reaching either end of its path of travel, at 105 which time the trunnions of the roller engage upon the short inclined surface 26^a so as to guide the said trunnions into the pockets 26. The center of the bearing pockets are spaced above the plane of contact of the ends of the 110

wear plate a distance slightly greater than that of the radius of the roller so that only an almost imperceptible rise or vertical movement is imparted to the roller when it 5 ceases to bear upon the wear plate and its trunnions come to bear in the pockets 26. Thus there is one point proximate to each 10 end of the path of travel of the roller where the load is transmitted both from the wear plate to the body of the roller and from the surfaces 26^a of the pockets to the trunnions, this point being where the trunnions first come to bear against said parts 26^a of the bearing pockets, as indicated in dotted lines 15 in Fig. 4. After this point is passed, the roller rotates in fixed bearings formed by the pockets 26, as shown in full lines in Fig. 4, without further longitudinal movement in the casing.

20 When the roller is released from the load imposed upon it by the body bolster 25, it will by gravity, roll on its trunnions inwardly toward the center of the casing, upon the inclined surfaces 26^a, the periphery 25 of the roller then engaging the associated end of the wear plate which, by reason of its top surface, as before mentioned, will act to center the roller with reference to the casing. Thus the roller is maintained at the 30 center of the casing when not transmitting load, without the aid of springs, where it is at all times ready to be engaged by the body bolster and to roll toward either end of the casing when load is again transmitted to it.

35 My improved bearing is made up of but few parts which may be easily assembled and which, when interposed between the truck and body bolster of a car, provides for a greater range of oscillation between said 40 bolsters, without increasing the size of the antifriction bearing.

While in describing my invention, I have referred to certain details of construction and relative arrangement of parts, I do not 45 wish to be limited thereto except as pointed out in the appended claims.

I claim as my invention:

1. In a truck bolster bearing, a casing 50 adapted for attachment to the truck bolster, said casing being open at the bottom and having flanges at the top defining a longitudinally extending slot, an antifriction roller projecting through said slot and having trunnions at its ends located below said

flanges, a filler block in the bottom of said 55 casing, said filler block having side members and a transverse bridge member, the bridge member being provided with an upwardly facing bearing surface for the roller, and the side members presenting arcuate bearing 60 pockets adapted to receive the roller trunnions at the ends of a pre-determined length of travel of said roller, said bearing pockets having downwardly inclined parts for returning the roller to its central position by 65 gravitation when the roller is released from load.

2. In a truck bolster bearing, a casing adapted for attachment to the truck bolster, said casing being open at the bottom and 70 having flanges at the top defining a longitudinally extending slot, an antifriction roller projecting through said slot and having trunnions at its ends located below said 75 flanges, a filler block in the bottom of said casing, said filler block having side members and a transverse bridge member, the bridge member being provided with an upwardly faced bearing surface for the roller, said bearing surface being inclined slightly 80 from both ends toward the middle, and the side members presenting arcuate bearing pockets adapted to receive the roller trunnions at the ends of a pre-determined length 85 of travel of said roller, said bearing pockets having downwardly inclined parts for returning the roller to its central position by 90 gravitation when the roller is released from load.

3. In a truck bolster bearing of the kind 90 described, in combination with a casing adapted for attachment to the truck bolster, a filler block adapted for location in the bottom of said casing, said filler block having side members and a transverse 95 bridge member, the bridge member being provided with an upwardly facing bearing surface and the side members presenting arcuate bearing pockets.

In testimony that I claim the foregoing 100 as my invention, I affix my signature in the presence of two witnesses, this 25th day of February, A. D., 1919.

ARNOLD A. WEIGEL.
